UNITED STATES PATENT OFFICE.

JAMES C. WENTZEL, OF GREENSBURG, PENNSYLVANIA.

RAIL-JOINT FASTENER.

SPECIFICATION forming part of Letters Patent No. 706,469, dated August 5, 1902.

Application filed November 9, 1901. Serial No. 81,747. (No model.)

To all whom it may concern:

Be it known that I, JAMES C. WENTZEL, a citizen of the United States, residing at Greensburg, in the county of Westmoreland and State of Pennsylvania, have invented certain new and useful Improvements in Rail-Joint Fasteners; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a rail-joint fastener, and has for its object to provide an improved device for securing the meeting ends of rails together in a convenient and inexpensive manner.

20 Other objects, as well as the novel details of construction, will be described hereinafter and illustrated in the accompanying drawings, in which—

Figure 1 is a side elevation of a rail-joint arranged in accordance with my invention. Fig. 2 is a longitudinal horizontal section through the same, and Fig. 3 is a vertical cross-section through the rails.

The reference-numerals 1 and 2 designate 25 two rails, adjacent the meeting edges of which are arranged angle-plates 3 and 4, which are adapted to secure said rails together. The angle-plate 3 is provided with keyhole-openings 5 in its side adapted to register with 30 openings 6 in the respective rails. Bolts 7 are designed to be passed through the plate 3 and through the opening in the rail and securely locked from the other side, as will be presently explained.

35 Each bolt comprises a shank having a head on one end, adjacent which is a longitudinally-arranged rib 8, adapted to engage in the keyhole-slot 5 of the angle-plate 3. The opposite end of the shank is cut away to form

shoulders 9 and 10, which are adapted to engage the keyhole-slots 11 in the angle-plate 4. The narrow portions 12 of the slots 11 are provided with faces or surfaces 13, upon which the shoulders of the bolt are adapted to slide, so as to bind said bolts securely to 45 the angle-plates and the rails. The wedges 14 are then inserted in front of the bolts, whereby accidental displacement of the same will be prevented.

50 When it is necessary to remove the angle-plate, it will only be necessary to take out the wedges or keys 14 and by sliding the angle-plates so as to make the bolts register with the openings, when they may be readily withdrawn.

55 I claim—

The combination with a pair of rails, of angle-plates secured in either side of the meeting edges thereof, one of said angle-plates having a keyhole-slot adapted to register with 60 an opening in the rail, a second angle-plate provided with a keyhole-slot in the narrow portion of which is arranged cam-surfaces, a bolt adapted to pass through each slot in the first-named angle-plate and provided with a 65 rib to fit in the narrow portion thereof, said bolt extending through the opening in the rail and through the slot in the remaining angle-plate, a shoulder formed on the bolt and adapted to engage the cam-surfaces of 70 the last-named angle-plate whereby said angle-plate may be reciprocated with relation to the rails to tighten the bolt, and a wedge 75 adapted to be inserted in the narrow portion of the slot to lock the angle-plate rigid with 80 relation to the bolt.

In testimony whereof I affix my signature in presence of two witnesses.

JAMES C. WENTZEL.
